UNITED STATES PATENT OFFICE.

ALEXANDER H. DREUX, OF BUFFALO, NEW YORK, ASSIGNOR TO F. N. BURT COMPANY, LIMITED, OF TORONTO, ONTARIO, CANADA, A CORPORATION.

CONTAINER.

Application filed May 18, 1926. Serial No. 109,846.

This invention relates generally to improvements in containers or receptacles, and has more particular reference to containers constructed of paper or similar material, 5 and having a removable cover frictionally or similarly held in closing position. It is adapted for containing materials of various character and is especially adapted and convenient for containing metal compacts and 10 similar articles.

It is a principal object of the invention to provide a container of the class mentioned having an improved arrangement for supporting a lining of flexible material, such 15 as satin or other fabric, in position for providing an attractive and durable interior lining which may also form a cushion or seat for the article which is to be placed in the container.

20 A further object is to provide a container of the class mentioned with an improved arrangement for frictionally retaining a closure tightly and securely in closing position in contact with a seal so as to constantly 25 maintain a tight closure and to prevent ingress of moisture, dust and other foreign matter, and to prevent egress of the contents.

20 A further object is to provide a container 30 of improved construction and arrangement, and of increased utility, appearance and simplicity of construction with consequent economy in manufacture.

Other objects will be in part pointed out 35 in connection with the following detailed description of an illustrative but preferred embodiment of the invention and will be in part pointed out in connection therewith.

The invention accordingly comprises an 40 article possessing the features, properties, and the relation of elements which will be exemplified in the article hereinafter described and the scope of the application of which will be indicated in the claims.

45 For a more complete disclosure of the nature and objects of the invention, reference is had to the following detailed description and to the accompanying drawing, in which:

50 Fig. 1 is a top plan view of a container constructed in accordance with the invention, the cover being partly broken away to reveal the interior construction, and

55 Fig. 2 is an enlarged vertical section taken approximately in a diametral plane.

Referring to the drawing for a detailed description of the illustrative embodiment of the invention there shown, the container includes a tubular body 5 which may be of any preferred shape but is shown as circular, that is, the body part of the container is cylindrical in form, which is convenient for many purposes. The body may be constructed of fibrous material such as paper, being preferably formed by winding a plurality of thin sheets of paper in superposed convolutions and adhesively attaching the successive layers together to form the complete body, which is thus of laminated construction.

The laminated tubular body 5 contains an inner laminated tubular body part 6 and a similar outer body part 7. At its upper and lower ends, the outer body part 7 extends beyond the inner body part, both at the bottom and top ends of the container. This arrangement of the body parts provides a circular groove 8 at the lower end or bottom of the container within which the edges of a circular disc or bottom 9 are secured in any convenient manner as by application of an adhesive. A finishing sheet may be pasted over the bottom, extending continuously over the margins of the bottom onto the sides to provide a reinforcing binder to hold the bottom in position, and additionally to provide an external finish for the container.

The top or upper projecting edge of the outer body part 7 is crimped or rolled inwardly to provide a bead 10 preferably extending continuously around the upper margin of the container and the inner lower side of which is disposed in proximity to the upper end of the inner body part 6, so as to form an annular groove 11 for the reception of the edges of a cover 12. The inner surface of the bead 10 lies outwardly of the inner surface of the inner body part 6, that is, the inner diameter of the bead is slightly greater than that of the inner body part 6 so as to provide an inwardly disposed ledge or seat 13 adjacent the bead 10 for the cover 12 to rest upon. The inner surface of the bead 10 preferably curves or inclines downwardly and outwardly at the lower part thereof, the bead itself being yielding and resilient due to the structure thereof and its position on the container. The cover 12 when bulged or curved upwardly as shown in the drawings, or even

when flat, being made of flexible material also may yield slightly when pressed into contact with the retaining bead 10. The cover being of slightly greater diameter than the minimum inner diameter of the bead, it will be seen, due to the yielding resilient engagement between the cover and the container, that said cover may be pressed downwardly past the bead into seated position upon the seat 13, and is held securely there either frictionally or otherwise by the engaging and slightly overlying surface of the bead. It will be understood also that the cover, by exertion of an outward pull thereon, may be similarly removed from closing position.

A lining 14, preferably of some soft fibrous or textile material, is secured in position within the container to line the surface thereof. In case a delicate article such as a metal compact or article of jewelry is to be boxed in the container, the lining 14 may be of a soft and ornamental fabric material, such as satin, so as to form a cushion seat for the article. The lining may lie in contact with the inner surface of the sides and bottom of the container and its upper edge is lapped over the cover seat 13 extending downwardly as at 15 between the adjacent tubular body parts 6 and 8, thus securely holding the lining in position. The lining may thus be supported in even and smooth condition upon the inner walls and bottom of the interior of the container, and the edge be curved in a uniform fold over the upper edge of the body part 6. The body parts may all be adhesively secured together, thus forming a strong container body and securely retaining the edges of the lining.

The lining preferably overlaps the cover seat 13 all the way around the container, and due to the soft yielding character of the lining material, a sealing element is provided which contacts with the underside of the cover edge. The cover being urged into seated position by engagement with the downwardly and outwardly curved surface of the inner side of the resilient bead 10 as above described, it will be seen that an effective seal is maintained when the cover 12 is in position so as to exclude dust, moisture, etc. and to prevent escape of the contents of the container, even when fine or powdered material is contained therein.

Since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of

the generic and specific features of the invention herein described, and all statements of the scope of the invention which, as a matter of language, might be said to fall therebetween.

Having described my invention, what I claim as new and desire to secure by Letters Patent, is:

1. A container including, in combination, a body including outer and inner tubular body parts, a fabric lining positioned within the inner body part for lining the interior of the container, said lining overlapping the top or outer edge of the inner body part to provide a sealing member at said outer edge and having its edges lying between said outer and inner tubular body parts for securing the lining in position, said outer body part extending at its top end beyond the inner body part and being provided at the extended part thereof with a crimp or roll providing a closure retaining bead positioned adjacent said top edge of the inner body part and providing a closure seating groove between said bead and said sealing member, and a removable closure having edges positioned in said seating groove and adapted to engage yieldingly with the container whereby said closure can be snapped past said bead into or out of closing position, and said seating groove and closure having mutually engaging contact surfaces cooperating by virtue of the yielding engagement between the container and closure when the latter is in closing position to yieldingly press said closure into sealing contact with said sealing member.

2. A container including, in combination, a body including outer and inner tubular body parts, said outer part extending at the top of the container beyond said inner part and being formed to provide a closure retaining bead adjacent to the upper end of said inner body part so as to provide, in conjunction with the latter, a closure receiving and retaining recess having a downwardly and outwardly inclined bounding surface, a sealing strip overlying the upper edge of the inner tubular body part at one side of said recess, and having its outer edge positioned between said inner and outer body parts to secure the sealing strip in position, and a removable closure formed to seat within said retaining recess with its edges spaced inwardly slightly from the inner surface of said outer body part and in yieldable engagement with said inclined bounding surface whereby said closure is yieldingly retained in closing position and yieldingly pressed into sealing contact with said sealing strip, said cover being removable outwardly from its seating recess past said retaining bead by virtue of said yielding engagement.

3. A container including, in combination,

a body having inner and outer tubular body parts, said outer part extending at the top of the container beyond said inner part and being turned inwardly to form a closure-
5 retaining bead lying adjacent to the upper end of said inner body part so as to provide in conjunction with the latter a closure-receiving and -retaining recess having a downwardly and outwardly inclined
10 bounding surface with the lower portion thereof positioned close to the top edge of said inner body part, said top edge of the inner body part extending inwardly of said inclined bounding surface to provide a
15 closure seat adjacent to said inclined bound-

ing surface, and a removable closure formed to seat within said retaining recess with its edges spaced inwardly slightly from the inner surface of said outer body part and with said edges in yieldable engagement 20 with said inclined bounding surface whereby said closure is yieldingly retained in closing position and yieldingly pressed into closing relation with said closure seat, said cover being removable outwardly from its 25 seating recess past said retaining bead by virtue of said yielding engagement.

In testimony whereof I affix my signature.

ALEXANDER H. DREUX.
